Primary Examiner — Prabhakar G Deshmukh*(74) Attorney, Agent, or Firm* — Honigman Miller Schwartz and Cohn LLP(57) CLAIM

The ornamental design for a combination table game, as shown and described herein.

DESCRIPTION

FIG. 1 is a top, front perspective view of a combination table game showing my new design; and,

FIG. 2 is a top, rear perspective view thereof.

The broken lines illustrate unclaimed portions and form no part of the claimed design.

1 Claim, 2 Drawing Sheets(56)
